UNITED STATES PATENT OFFICE.

URI D. MANVILLE, OF NEW HAVEN, CONNECTICUT, ASSIGNOR TO THE ELM CITY COMPANY, OF SAME PLACE.

DESIGN FOR NECK-RUFFS.

Specification forming part of Design No. **7,116**, dated January 20, 1874; application filed January 7, 1874.
[Term of Patent 7 years.]

To all whom it may concern:

Be it known that I, URI D. MANVILLE, of New Haven, in the county of New Haven and State of Connecticut, have invented a new Design for Neck-Ruff; and I do hereby declare the following, when taken in connection with the accompanying drawing and the letters of reference marked thereon, to be a full, clear, and exact description of the same, and which said drawing constitutes part of this specification and represents a front view.

This invention relates to a design for a ruffe for the necks of ladies' dresses, and commonly called a "neck-ruff;" and the design consists in a succession of vertical plaits rising from a band, and at the front ends a diagonal plaited fly hanging from the upper edge of the

band, as shown in the accompanying illustration.

A is the band, forming the lower edge of a vertical ruffle made in a succession of plaits to extend around the neck. At the front ends is a fly, B, of triangular form, made in plaits, and joining the vertical plaits at the band and hanging point downward, as shown.

I claim as my invention—

The design for neck-ruff, formed of the vertical plaited ruffle and the plaited triangular fly at each end, as shown in the accompanying illustration and herein described.

URI D. MANVILLE.
